TELEVISION CABINET

Arnold R. Dahlberg, Minneapolis, Minn., assignor to
The Dahlberg Company, a corporation of Minnesota

Filed Apr. 22, 1959, Ser. No. 55,611

Term of patent 14 years

(Cl. D56—4)

Fig. 1 is a perspective view of a television cabinet showing my new design;

Fig. 2 is a top plan view;

Fig. 3 is a side elevational view, the side not shown being substantially the same in appearance; and

Fig. 4 is a rear elevational view thereof.

The characteristic features of my design reside in the configuration of the visual station indicator and its relationship to the television cabinet proper.

I claim:

The ornamental design for a television cabinet, as shown and described.
